UNITED STATES PATENT OFFICE.

LEWIS STERLING SUTLIFF, OF CHARLESTON, SOUTH CAROLINA.

SWITCH.

1,392,665.

Specification of Letters Patent.

Patented Oct. 4, 1921.

Application filed June 23, 1920. Serial No. 391,037.

To all whom it may concern:

Be it known that I, LEWIS STERLING SUTLIFF, a citizen of the United States, and a resident of Charleston, in the county of 5 Charleston and State of South Carolina, have invented certain new and useful Improvements in Switches, of which the following is a specification.

My invention has reference to switches 0 and more particularly to a simple and novel switch designed for controlling an electric circuit and thus the working apparatus or instrumentality interposed in the circuit.

Among the objects of the invention are 15 to provide a switch which may be used as a wall switch, a suspended switch or a straight line switch; to permit the device to be operated in either use, by one hand and which will indicate its position without the 20 necessity of employing the characters "On" and "Off" as usual in snap switches; to so construct the device that its parts are reduced to the lowest minimum, while still permitting the removal of the contacts in 25 order to facilitate the attachment of the circuit wires in order to facilitate installation and repair, and to so construct the switch that it may be used for the installation of line wires which pass through it or which 30 terminate at the switch, whereby the device is adapted to a variety of uses.

Other and further objects of my invention will become readily apparent to persons skilled in the art, from a consideration 35 of the following description when taken in conjunction with the accompanying drawings, wherein:—

Figure 1 is a side view of the switch,
Fig. 2 is a front elevation,

Fig. 3 is a face view of the rear section,
Fig. 4 is a face view of the front section,

Fig. 5 is a top plan view partly in transverse section,

Fig. 6 is a perspective view of one of the 45 contacts or terminals,

Fig. 7 is a similar view of the other contact or terminal, and

Fig. 8 is a side view partly in section and broken away to show the device employed 50 as a wall switch.

Referring to the drawings in detail, in which like reference characters designate corresponding parts throughout the several views, my improved switch is shown as comprising a pair of disks which are flat and relatively thin, being a front disk 10 and a

rear disk 11. These disks or plates are of any required dimension or shape, and of any suitable non-conductive or dielectric material, such as porcelain, hard rubber or fiber, 60 though preferably made circular in outline, as indicated in the drawings. The disks are disposed with their inner faces in contact as indicated at 12, and both are provided with central apertures 13 receiving a pivot 65 in the form of a bolt or the like 14, having suitable means for maintaining the disks in frictional contact and for regulating the freedom of movement therebetween, as by means of the lock nut and washer 15 70 preferably located at the back of the switch while the head of the bolt is positioned at the front. Of course, it is to be understood that any suitable adjustable or regulatable connection may be employed between the 75 disks or sections of the switch constituted by the circular or rather geometrical plates 10 and 11.

Extending radially from each of the disks is a pair of operating and condition indicating projections, the projections 16 and 17 of the disk 11 being disposed diametrically opposite and extending radially outward. The projections 18 and 19 of the disk 10 also project radially outward but are so 85 related to the circumferential edge of the disk that when one of the projections is in alinement with the corresponding projection of the other disk, the opposite projection will be disposed out of alinement with its 90 corresponding projection and spaced therefrom circumferentially. That is, the projections 16 and 17 are located diametrically opposite with an arc of 180° on either side and the projections 18 and 19 are so related 95 to the edge of the disk thereof that the arc on one side is less than 180°, preferably about 150°, and the arc at the other side describes an angle of more than 180°, and preferably 210°, thereby necessitating oscillatory movement of the front disk in order to aline either one of its projections with the corresponding projection of the rear disk and in this way controlling the circuit by operation of the switch in a manner to be 105 hereinafter more fully pointed out. It will thus appear that the disks are adapted to move relatively, one turning on the other or both moving on the axis formed by the bolt or pivot 14 in order to obtain a certain 110 relative position of the projections of one disk relative to the projections of the other

disk. The purpose of this is to cut the circuit in or out by means of a plurality of contacts, the mounting of which will now be described.

5 At the inner or rear face of the front disk 10 there is disposed a contact or bridge plate 20 of current conducting material such as copper, and said plate is of arcuate formation, being curved concentric to the axis of 10 the disk or plate forming the front section of the switch proper. It fits a corresponding recess 21 at the inner face of the disk and is provided with angularly directed ends 22 embedded in corresponding recesses in the 15 disk. At its outer edge it is formed intermediately with a right angular projection 23 also embedded in the inner face of the disk and slightly projecting from the plane of the inner surface of the plate and disk so 20 as to form a detent by co-operation with a notch or recess extending radially of the outer or front face of the disk 11 as indicated at 24, in order to retain the disk against relative movement when the circuit 25 is closed, as will be hereinafter more fully explained. In order to securely anchor the plate or bridge piece 20 in position, the latter is provided at its arcuate or concaved edge which is disposed toward the axis, with 30 a right angular dove-tail projection 25 engaging a corresponding recess 26 in the inner face of the disk 10, the recess 26 having a greater maximum depth than the recess 35 accommodating the bridge piece or plate proper. By this means, the bridge piece is rendered detachable and may be readily applied or removed for renewing or replacing the same when worn out or broken.

The face of the disk 11 disposed toward 40 the disk 10, is provided with a substantially reverse disposed C-shaped recess or groove 27 disposed concentric to the axes of the disks, that is, the semi-circular recess is provided at one side of a diametrical line bisecting the disk at right angles to the diametrical line connecting the projections 16 and 17, with extensions 28 at the opposite side of the diametrical line, at which points on the periphery of the disk, there are provided 45 openings or slots 29, the grooves or extensions 28 of the groove 27 being spaced apart adjacent to the projection 16 as indicated at 30 and receiving contact plates or terminals 31. These contact plates or terminals 50 are preferably of right angular formation, the vertical portions thereof entering grooves 32 at the ends of said grooves or groove extensions 28 and at either side, so as to extend in a plane parallel with the axis, the top 55 portions of the plates being tapered toward each other and seated in the faces of the disks or in recesses therein so as to project slightly from the plane of the face like the bridge piece or plate 20. The plates are 60 apertured to receiving binding screws or ter-

minals 33 which serve for the connection of oppositely branching electrical conduits or wires 34 and 35 which extend around the grooves 28 and out through the slots or openings 29 in conjunction with a second 70 conduit or wire 35, although it is to be understood that one of the wires, such as the wire 34, may be eliminated and wire 35 connected to the terminal screw and contact 75 where the switch is used as a suspended switch instead of a straight line switch intermediately of the source of energy and the machine, apparatus or instrumentality to be operated.

Thus, with the switch arranged to accommodate two strands of electric wire entering the switch and which it is desired to connect or disconnect by means of the switch through the medium of the contacts or metal plates of conducting material of suitable shape, such as described, and to which the wires are connected so as to be readily attached or detached by means of screws or other suitable fastening means, the circuit may be closed or opened, that is 90 cut in or out by one hand through the medium of grasping the projections at either side with the thumb and forefinger, and when the bridge piece is positioned to engage both of the plates 31, the circuit will 95 be closed. In this position, the projections 17 and 19 will be in alinement, the projection 17 having been grasped with the thumb and the projection 19 with the forefinger, with rotation imparted to the disks, sufficiently to revolve or turn the same relatively or one independently of the other in order that the projection 18 will be moved 100 out of alinement with respect to the projection 16. By then engaging the projections 105 16 and 18 by the thumb and forefinger respectively, the disks may be rotated so as to move the contact plate or bridge piece 20 out of engagement with one of the plates or contacts 31, preferably the upper one, 110 thus moving the projections 17 and 19 out of alinement. This may be indicated if desired by an arrow pointing to a position intermediate or bisecting the arc between the projections 16 and 17, as indicated at 36, 115 with the word "On" adjacent thereto, or the projections 16 and 17 may be marked so as to expose the "on" and "off" indications according to the position of the switch. However, such markings are generally unnecessary in the construction devised. When the switch is in the on or closed position with the plate or bridge piece 20 bridging the contacts 31, the projection or detent 23 engaging the recess 24, will hold the switch 125 against movement and frictional engagement between the parts including the disks and will hold the switch in any desired position. This obviates the necessity of employing springs or other complicated parts 130

present in switches and reduces the number of parts, and the cost of production to a minimum, as well as rendering the same unlikely to get out of repair or order. One disk may be turned to the right or left about one-eighth of a revolution with respect to the other disk, instead of turning both relatively, to bring the projections into alinement and by the construction devised, the switch may be readily operated with one hand, sufficient pressure being applied by the forefinger and thumb so as to bring the bridgepiece into engagement with the spaced contacts by spanning the same or to disengage from one in order that the circuit will be opened.

It will also be understood that the switch may be readily operated with one hand whether it be securely fastened to a stationary object or only suspended from overhead by the electric cord it is designed to operate when used as a wall switch, as distinguished from a suspended switch or a straight line switch, it being understood that the switch affords every facility of the more complicated types of switches commonly used for these purposes. There is shown in Fig. 8 of the drawings, the device shown applied to a wall as a wall switch, the wall being designated at 37 and screws 38 passing through the disk 11 from the covered or front face thereof and through ferrules or bushings 39 to space the switch from the wall so as to accommodate the connecting means, as well as to comply with regulations and insure perfect insulation. Of course, the wall may be substituted by any stationary object, the screws being of suitable dimension and passed through holes in the disk 11 above and below the center aperture or opening therethrough constituting the axis of the disk, the heads of the screws being countersunk so as not to engage the flat face of the disk 10. Of course, the ferrules 39 may be omitted if desired but are employed where it is desired to have the switch stand out from the surface to which it is secured, the screws passing through the ferrules, as shown. Furthermore, by reason of the openings provided at the top and bottom of the switch, means is provided for installation where both wires of a line enter the switch and pass through it, one line being cut and the ends secured to the terminals of the disk 11 and the other passing through intermediately of the source of energy and instrumentality to be operated, especially adapted for use on electric iron cords, etc., while as previously stated, the switch may be located intermediately of one wire or cord or as a suspended switch in order to control a light or fan above or at any distant point. The novelty of the switch is to be found in its simple construction, its operation by

means of projections or lugs on the circumference of the disks, the small number of parts required in its construction, and its adaptation to various uses instead of a differently designed switch for each use.

In view of the foregoing, it is thought that the operation of the device will be readily understood and in view of the simplicity and practical value that it will commend itself to those skilled in the art.

Having thus described my invention, what I claim is:—

1. A switch of the class described comprising a pair of disks axially connected for movement one with respect to the other, one of said disks being provided with a bridge piece and the other provided with contacts adapted to be spanned by the bridge piece for controlling an electrical circuit including said contacts, said disks being provided with recesses adapted to accommodate circuit wires connected to said contacts, and integral radial projections on the peripheries of said disks for movement into and out of alinement whereby to move said bridge piece into position to span said contacts to close the circuit therethrough and for movement out of engagement with one of said contacts.

2. A switch comprising a pair of circular disks of dielectric material, means to connect said disks for relative movement of one with respect to the other, one of said disks being provided with diametrically opposite lugs and the other disk being provided with similar lugs located in closer angular relation than the first named lugs, whereby when the lugs at one side are disposed in alinement, the lugs at the other side will be spaced apart, circuit wires having contacts arranged in one of said disks, a second circuit wire passing between the disks, and a bridge piece carried by the other disk and movable into engagement with both of said contacts to close the circuit therethrough or out of engagement with one of said contacts.

3. A switch of the class described comprising a pair of disks, axial connecting and clamping means for the same, one of said disks being provided with a groove concentric to its axis and a pair of contacts forming termini of circuit wires, said groove being of C-shaped formation and having openings leading through the periphery of the disk, a circuit wire extending through said openings and positioned in said groove at one side of the axis of the disk, a detachable contact plate carried by the other disk and adapted to span said first named contacts to close the circuit therethrough, one of said disks being provided with opposed radial projections and the other disk having similar projections located at an angle of less than 180° from each other whereby to permit the projections at either side to be

moved into alinement by grasping the same simultaneously or simultaneously applying pressure thereto to turn the disks relatively.

4. A switch of the class described, comprising a circular disk having diametrically opposed projections, said disk being of dielectric material and having at its inner face a concentric groove provided with projections at one side and openings through the edge portion of the disk, terminal plates detachably secured at the end walls of said extensions and provided with wire attaching means, a second disk having a detachable contact plate embedded therein to engage said first named plate or for movement out of engagement with respect thereto, means for connecting said disks axially for frictional contact and adjustment, and cooperating projections on the edges of the disks for partially turning one with respect to the other and bringing the projections at one side into alinement alternately with respect to the alinement of the projections at the opposite side.
5. A switch comprising the combination with supporting means; of a pair of relatively flat disks of non-conductive material, an axial connection between the disks whereby one is rendered movable with respect to the other and adapted to be held in an adjusted position, one of the disks being provided at its contacting face with a semi-circular groove having end openings extending through the periphery and extensions also extending concentrically to the axis, right angular contact plates embedded in the ends of said extensions and provided with suitable binding terminals, said disk also having a recess between said contact plates, a curved plate having a dovetailed offset extension embedded in the coacting face of the other disk and arranged concentric to the axes of the disks for engagement with said first named contact plates and adapted to span the same, said arcuate or curved plate having a spring projection designed to engage said notch in one position, and a pair of projections at the periphery of each disk and adapted to be alternately grasped and moved into alinement at diametrically opposite sides of the disks to open or close the switch.

the ends of said extensions and provided with suitable binding terminals, the adjacent face of the other disk being provided with a recess and a contact plate of arcuate 40 formation mounted in said recess and detachably secured to said disk for coöperation with the first named contact plates.

6. A switch comprising the combination with supporting means; of a pair of relatively flat disks of non-conductive material, an axial connection between the disks whereby one is rendered movable with respect to the other and adapted to be held in an adjusted position, one of the disks being provided at its contacting face with a semi-circular groove having end openings extending through the periphery and extensions also extending concentrically to the axis, right angular contact plates embedded in 55 the ends of said extensions and provided with suitable binding terminals, said disk also having a recess between said contact plates, a curved plate having a dovetailed offset extension embedded in the coacting 60 face of the other disk and arranged concentric to the axes of the disks for engagement with said first named contact plates and adapted to span the same, said arcuate or curved plate having a spring projection designed to engage said notch in one position, and a pair of projections at the periphery of each disk and adapted to be alternately 65 grasped and moved into alinement at diametrically opposite sides of the disks to 70 open or close the switch.

LEWIS STERLING SUTLIFF.
